Des. 1130

Elémir J. Ney & Lowell. No. 1.
Assignor to
The Lowell Manufacturing Co. Lowell.
Letters Patent No. 1130. Dated Aug. 9. 1859.

The schedule referred to in these Letters Patent and making part of the same.

To all whom it may concern:

Be it known that I, Elémir J. Ney, of Lowell, in the County of Middlesex and State of Massachusetts, have originated and designed a new pattern

for carpets or other fabrics, of which the following is a full, clear and exact description, reference being had to the accompanying drawings making part of this specification.

The corner A, is a quarter of a figure composed of dotted (1) and plain (2) diamonds, surrounded by the striped belt 3.

Corner B, is a quarter of a figure composed of leaves 4, and flowers 5, resting on the pointed figure 6, the whole being surrounded by the belt 7.

C, in the center is a plain leaf, resting on the pointed scroll 8, which runs through the whole design, slightly overlapping the belts 3 & 7, and covering a portion of the corner figure A.

At the corners D and E are the circles 9, being irregularly one upon another, the highest being the quarters of a circle 10.

The colors employed in the different portions of the design, may be varied to suit the taste and wish of the manufacturer.

Claim.

What I claim as my invention, and desire to secure by Letters Patent, is the design or pattern for carpets herein set forth.
